ANTI-JIMMY TUBULAR LOCK

Henry G. Voight, Hamden, Conn., assignor to Sargent & Company, New Haven, Conn., a corporation of Connecticut

Application October 4, 1943, Serial No. 504,817

2 Claims. (Cl. 292—198)

1

This invention relates to door locks, and more particularly to a door lock of the so-called night latch type, which is provided with a rotating bolt designed to cooperate with a keeper on the door jamb, which keeper is in the form of a stud or post.

It is well known that doors are very often forced by the insertion of a tool between the door and door jamb, and by means of this tool forcing the door away from the jamb to a sufficient extent to disengage the bolt from the keeper, and in some instances means have been provided to prevent such an operation.

The lock of the present application is designed to be "jimmy-proof" in this respect, as interengaging means are provided on the keeper and bolt to prevent the forcing apart of these two elements, and therefore prevent their disengagement.

As illustrated, the lock is shown as a tubular lock or one in which the parts are contained in a substantially tubular case which may be inserted in a circular opening or bore drilled through the edge of the door. Moreover, the bolt is mounted in the lock for rotation about the same axis as that of the tubular case, that is, about an axis perpendicular to the plane of the edge of the door, the bolt projecting from the edge of the door for engagement with the keeper. Also means are provided for positively dogging the bolt against rotation when it is in engagement with the keeper, so that the door may not be opened without a manual operation to withdraw the dog from operative position. That is to say, the door handle or knob or key-operated means must be manipulated to open the door, as distinguished from some locks of a similar character wherein the bolt is merely releasably held in position so that the door may be opened by a push or pull thereon.

One object of the present invention is to provide a jimmy-proof door lock having a projecting bolt mounted for rotating movement.

A further object of the invention is to provide a door lock having a bolt designed to rotate on an axis perpendicular to the plane of the edge of the door and means for preventing disengagement of the bolt from the keeper by an instrument inserted between the door and door jamb.

A still further object of the invention is to provide a tubular lock having a bolt mounted therein to rotate about the axis of the tubular case, which bolt is provided with means by which it is positively dogged in its locked position, but which may be rotated from unlocked to locked

2

position by engagement with the keeper when the door is being closed.

To these and other ends the invention consists in the novel features and combinations of parts to be hereinafter described and claimed.

In the accompanying drawing:

Fig. 1 is a sectional view of a lock embodying my improvements, shown mounted upon a door;

Fig. 2 is a face view of the lock case showing the bolt projecting therefrom;

Fig. 3 is a sectional view on line 3—3 of Fig. 2;

Fig. 4 is a rear elevational view of the bolt member;

Figs. 5 and 6 are diagrammatic views showing the operation of the bolt as it approaches and engages the keeper; and

Fig. 7 is a sectional view on line 7—7 of Fig. 1 on a reduced scale.

To illustrate a preferred embodiment of my invention I have shown a door at 10, cooperating with a stop 11 on the door jamb 12. Within a circular opening 13 in the door is mounted a lock case 14 of generally tubular shape, the case being provided with a front plate 15 and a finish plate 16 secured thereto.

The bolt is rotatably mounted adjacent the front end of the case, and comprises a body portion 17 and a projecting head 18 connected to the body by a neck 19 extending through the plates 15 and 16, this neck being provided with a reduced portion 20 having shoulders at each side thereof so that the bolt will be held against longitudinal or axial movement relatively to the case. It may be noted that the body portion 17 fits snugly within the case and is of generally cylindrical shape, so that the bolt will be rotatably carried by the case.

As shown in Figs. 2, 5 and 6, the bolt head is of circular shape and is eccentrically mounted with respect to the neck 19 and the body 17 so that the larger area of the bolt stands above its axis. The bolt is provided with a slot 21 opening through the periphery thereof, this slot being designed to receive and cooperate with a keeper 22

in the form of a stud secured to the door jamb and projecting toward the face of the door. As shown, this stud is somewhat longer than the thickness of the bolt 18, and thus projects through the slot to the far side of the bolt head and is provided with a head 23 on its projecting end, the diameter of the head being greater than the width of the slot 21.

As shown in the diagrammatic views, Figs. 5 and 6, the parts are mounted in such relation that, as the door is closed the keeper will enter

the mouth of the slot and strike against the longer or upper wall thereof, thus rotating the bolt through a small angle as the door is further closed. Fig. 5, for example, shows the position of the parts as the door approaches closed position and the keeper 22 engages against the longer wall of the slot 21. It may be noted that this slot is non-radially disposed with respect to the center of the bolt head. As the door is further closed the bolt head 18 is rotated to the position shown in Fig. 6, in which the keeper 22 is embraced by the walls of the slot 21. It will be obvious that the door will now be held in closed position when the bolt is prevented from rotating from the position shown in Fig. 6, but that if the bolt is released a pull upon the door will serve to open the same, the bolt being reversely rotated during the opening movement to the position shown in Fig. 5, where it will again stand ready to receive the keeper when the door is closed.

Means are provided to dog or hold the bolt in the position shown in Fig. 6, and also to releasably hold it in the position shown in Fig. 5. In the latter position, however, the bolt will be free to be rotated by engagement with the keeper, and when rotated to the position in Fig. 6, will be automatically dogged.

For this purpose a yoke 25 is slidably mounted in the case 14, the yoke being provided with guide lugs 26 slidably received in slots 27 at the rear end of the case. Secured at the front of the yoke 25 is a forwardly projecting dog 28 designed to be received in a slot 29 extending across the rear face of the bolt. The yoke is urged forwardly by a compression spring 30 which tends to maintain it in its forward position in engagement with the body 17 of the bolt.

The dogging member 20 extends across the rear face of the bolt body, its length being substantially equal to the diameter of this body, and the width of the dogging member is such that it fits snugly within the slot 29. The body of the bolt is also provided with a second slot 31 upon its rear face, which slot intersects the slot 29 at a slight angle thereto, which angle corresponds to that between the positions of the bolt head shown in Figs. 5 and 6. The wall of the slot 31, which is adjacent the slot 29, is beveled, as shown at 32, and the dog 28 is provided with a complementally beveled surface 33 so that when the dog stands in the slot 31 the bolt may be rotated if a sufficient torque is exerted thereon, and the dog 28 cammed rearwardly by the cooperation of the cam surfaces 32 and 33 against the action of the spring 30. It will, however, be understood that when the dog 28 lies in the slot 29 the bolt will be positively held against rotation.

Means are provided at the inside and outside of the door for withdrawing the dog from the slot 29 so that the door may be opened. For this purpose a hub 35 is rotatably mounted in the lock case, this hub carrying a rollback 36 acting against the lugs 26 to withdraw the dog-carrying yoke 25. The hub 35 is provided with a non-circular opening 37 through which extends a spindle 38 having a knob 39 secured thereto at the inside of the door, the knob being mounted upon an inside escutcheon 40.

An escutcheon 41 is secured at the outside of the door by means of screws 42 passed through the inner escutcheon and entering lugs 43 provided on the outer escutcheon. A lock such as a pin tumbler lock 44 is mounted in the escutcheon 41, the lock having a key barrel 45 having connection with the stem 38 so that the door may be

opened from the outside by means of a key. In order that the inside knob may be operable without turning the key barrel, a lost-motion connection is provided between the key barrel and the stem 38, such, for example, as that shown in Patent No. 2,124,897, granted to John H. Shaw July 26, 1938.

The lock 44 is provided with a face member 47 of greater size than the opening in the escutcheon 41 through which the body of the lock is inserted, and the lock may be held in place after being inserted through the face of the escutcheon by screws 48 passing through a plate 49 within the escutcheon and being threaded into wings 50 secured to the body of the lock.

The operation of the lock is as follows: When the door is in open position it will be understood that the dogging member 28 stands in the slot 31, and that the bolt head 18 stands in the position shown in Fig. 5. As the door is swung to closed position the body of the keeper 22 strikes against the longer wall of the slot 21 and serves to rotate the bolt to the position shown in Fig. 6 when the door is fully closed. This rotation of the bolt by engagement with the keeper member will serve to cam the dog 28 out of the slot 31 against the action of the spring 30 by reason of the cooperation of the beveled surfaces 32 and 33. When the bolt has reached the position shown in Fig. 6, the dog 28 will be projected forwardly by the spring 30, and will enter the slot 29, thus dogging the bolt against rotation and holding the door firmly in closed position.

The operation of opening the door may be effected either by the knob from the inside or by a key from the outside, either of which will serve to rotate the spindle 38; and thus through the rollback 36 move the yoke 25 rearwardly and withdraw the dog 28 from the slot 29. At this time the bolt will be free for rotation and the door may be freely opened by a pull or push thereon. This opening movement of the door will serve to effect a reverse rotation of the bolt from the position shown in Fig. 6 to that shown in Fig. 5, so that when the key or knob is released the dog 28 will be projected into the slot 31 by the action of the spring 30 in order to releasably hold the bolt in the proper position to receive the keeper when the door is again closed.

It will also be noted that the keeper 22, as shown in Fig. 1, projects through the slot in the bolt head and extends to the far side of the latter. The head 23 on the keeper, being slightly larger than the width of the slot 21, will prevent the separation or disengagement of these parts by a tool inserted between the door and the jamb. The lock is, therefore, jimmy-proof in that the door cannot be pried away from the jamb to a sufficient extent to disengage the bolt head from the keeper.

While I have shown and described a preferred embodiment of my invention, it will be understood that it is not to be limited to all of the details shown, but is capable of modification and variation within the spirit of the invention and within the scope of the claims.

What I claim is:

1. A door lock comprising a case of generally tubular shape, a bolt rotatably mounted in the case and projecting therefrom, said bolt having a body portion snugly fitting said case, a head portion lying without the case, and a neck portion connecting said head and body and passing through an opening in the front of the case, said neck portion being of reduced size with respect

to said head and body and being provided with means engaging the front face of the case to prevent movement of the bolt in an axial direction.

2. A door lock comprising a case of generally tubular shape, a bolt rotatably mounted in the case and projecting therefrom, said bolt having a body portion snugly fitting said case, a head portion lying without the case, a neck portion connecting said head and body and passing through an opening in the front of the case, said neck portion being of reduced size with respect to said head and body and being provided with means engaging the front face of the case to prevent movement of the bolt in an axial direction, a dogging member engaging the rear face of the bolt body to restrain the bolt against movement and means including a rotatable knob member to withdraw said dogging member from engagement with the bolt.
